FIREARM

Filed May 5, 1926

UNITED STATES PATENT OFFICE.

CRAWFORD C. LOOMIS, OF ILION, NEW YORK, ASSIGNOR TO REMINGTON ARMS COMPANY, INC., A CORPORATION OF DELAWARE.

FIREARM.

Application filed May 5, 1926. Serial No. 106,817.

This invention relates to the action locking mechanism for repeating guns and more particularly to a means for preventing blocking or returning movement of the firing mechanism by parts of the action bar locking mechanism.

In repeating guns, it is customary to provide the device for locking the breech closing and reloading mechanism against operation 10 when the gun is in condition for firing. This is done not only for the purpose of preventing waste of ammunition by the ejection of unfired cartridges, but also to serve as an indicator that the gun is in condition for firing. 15 Such locking device ordinarily comprises a member which is in the path of movement of a part of the breech opening and re-loading mechanism when the gun is cocked and is moved out of the path to ineffective position 20 by the firing movement of the hammer, or some part associated with the hammer. If the re-loading mechanism is pressed firmly into contact with this locking member, the friction between the contacting parts may be 25 sufficient to prevent movement of the locking member and this member in turn may block the movement of the firing hammer and cause the gun to misfire, or cause a breakage of some part of the mechanism. In guns in which 30 the re-loading operation is performed by reciprocation of an action bar associated with the forearm there is a strong tendency for the shooter to draw the action bar into firm engagement with its locking member, since 35 the gun is held against the shoulder by means of the forearm.

The present invention contemplates the provision of a mechanism whereby the firing hammer may execute its full movement, even 40 though the action bar locking member is held in the locking position in which it would normally block the movement of a member associated with the firing hammer. For the purpose of illustration, the invention has been 45 shown as applied to a firearm of the type described in Patent 908,883, granted February 6, 1906, to John D. Pedersen.

In the drawings:

Figure 1 is an elevation partly in section 50 of a part of a firearm embodying the present invention, the breech being closed and locked, the hammer cocked, and the action bar locked.

Figure 2 is a section through the receiver

of the firearm showing the hammer in its forward position and the action bar is still 55 locked.

Figure 3 is a section similar to Figure 2, showing the action bar lock in ineffective position.

Figure 4 is an enlarged detail view of a 60 part of the hammer spring rod constructed according to the present invention.

Figure 5 is an enlarged detail showing the carrier latch in engagement with the hammer 65 rod.

The firearm illustrated in the drawings comprises a receiver 11, having a stock 12 suitably secured at its rear end and a barrel 13 secured at its forward end. The receiver contains a breech block 14 formed with a locking shoulder 15 adapted to engage a recoil shoulder 16 in the top of the receiver thereby locking the breech block in breech closing position. The breech block comprises a downwardly extending foot 17 adapted to engage 70 a suitably shaped part of an action bar or slide 18 by means of which the breech block is moved downwardly to disengage the locking shoulder 15 from the recoil shoulder 16 and is subsequently retracted to open the breech. 75 The action bar 18 has a bearing in an opening 19 in the receiver, and is provided with an operating handle or forearm 20. In the firearm illustrated in the drawings, the action slide is of hollow tubular form and also 80 serves as a cartridge containing magazine. 85

The bottom of the receiver is closed by trigger plate 25 which is fixed to the stock 12, said trigger plate serving as a support for a trigger 26 mounted on pivot 27, and also 90 carrying a bearing sleeve 28, upon which are pivotally mounted the firing hammer 29 and the member 30, which, in this construction, serves both as an action bar lock or latch, and as a carrier for moving the cartridges one at 95 a time from the tubular magazine action bar 18 into alignment with the barrel chamber. This latch lever member 30 is provided with a rearwardly extending arm 31 which overlies a plunger 32 mounted in a recess in the trigger, and is pressed upwardly into engagement with the arm 31 by coil spring 33. By means of this spring and plunger, the trigger is tensioned forwardly, and the forward end of the member 30 is pressed downwardly; its movement in this direction being stopped by its 100 105

contact with the bottom wall of the receiver at 34. Member 30 is provided at its forward end with a locking face 35, which when the forward end is depressed stands opposite a lug 36 mounted in one side of the tubular action bar 18. The lug 36 has a spring mounting which permits it to be deflected outwardly when engaged by a cam face 37, located on the forward end of the member 30 immediately below the locking face 35.

It will be seen that when the gun is cocked, the several parts which have been described occupy the position shown in Figure 1, the latch member 30 being rocked by spring 33 so that the locking face 35 is in alignment with the action bar lug 36, and the action bar is locked thereby. By rocking the forward end of latch member 30 upward to bring cam face 37 opposite lug 36 the action bar may be released for rearward movement. At the end of the rearward stroke of the action bar lug 36 engages a cam slot 38 in the side of member 30, and on the forward stroke of the action bar lifts member 30 to transfer a cartridge into alignment with the chamber. The means for withdrawing latch member 30 from action bar locking position is associated with the hammer actuating devices. These devices comprise a main spring 39 surrounding a main spring rod 40, which is pivoted to the hammer at 41. The enlarged head 42 of the main spring rod comprises an arcuate depression 43 near its forward end to provide clearance for the part of latch member 30 which surrounds its pivot. The main spring rod is bifurcated by a horizontal longitudinal slot 44 extending rearwardly from the center of the depression 43, thus forming a free end or arm 45 for a purpose which will be herein-after described.

In the normal operation of the gun, when the trigger is pulled, the hammer is driven forward by the power supplied by the main spring 39, and as it approaches its forward position (Figure 2), the inclined end 46 of the arm 45 engages the rearwardly extending arm 31 of latch member 30, rocking this member about its pivot to the position shown in Figure 3, thus releasing the action bar. If, however, at the time the hammer falls, the action bar is drawn too strongly to the rear, the locking lug 36 will be pressed so tightly into engagement with the locking face 35 that movement of the latch member 30 upon its engagement by the end of arm 45 will be prevented. In this event, arm 45 is deflected upwardly to the position shown in Figure 2 and thus the main spring rod and the hammer are permitted to perform the complete firing movement without encountering a resistance of such magnitude as to appreciably retard their movement and thereby cause any tendency to misfire. A forceful blow of the hammer is thus insured, even the latch member 30 be held against movement. The arm 45,

which is sufficiently rigid to effect the movement of the latch under normal conditions, is tensioned when forced upwardly to Figure 2 position, thus when the action bar is subsequently released this arm will return to normal position and upon such movement will rock the latch member 30 and withdraw it from effective position.

It is to be understood that the foregoing description and the drawings merely set forth a typical embodiment of inventions which may take a variety of forms falling within the scope of the appended claims.

I claim:

1. In a firearm of the type having a firing chamber, breech mechanism closing said firing chamber, and operating mechanism for said breech mechanism, the combination of a latch normally blocking movement of said operating mechanism, a firing hammer, a latch disabling means associated with said hammer and comprising a bifurcated member, one arm of which is adapted to yield if the resistance to motion of said latch is excessive.

2. In a firearm of the type having a firing chamber, breech mechanism closing said firing chamber, and operating mechanism for said breech mechanism, the combination of a latch normally blocking movement of said operating mechanism, a firing hammer, a bifurcated member having one arm attached to said hammer and a second arm adapted to engage and operate said latch, but to yield if the resistance of said latch to movement is excessive.

3. In a firearm of the type having a firing chamber, breech mechanism closing said firing chamber, and operating mechanism for said breech mechanism, the combination of a latch normally blocking movement of said operating mechanism, a firing hammer, an actuating device for said hammer comprising a rod pivoted thereto, said rod being slotted to provide a free end adapted to normally withdraw said latch from effective position, and to yield if the resistance of said latch to motion is excessive.

4. In a firearm, in combination an impact member, actuating means therefor including a bifurcated rod, a latch device normally actuated by engagement with one arm of said bifurcated rod, said arm being deflected and tensioned by engagement with said latch device if the resistance to movement of said latch device is excessive.

5. In a firearm, in combination, an impact member, actuating means therefor, a latch device, means normally effective on the movement of said impact member to withdraw said latch device from effective position, said means including a bifurcated rod, one arm of which is adapted, on movement of said impact device, to engage said latch and to be deflected and tensioned if the resistance to movement of said latch is excessive, and, by

its return to normal position, to subsequently withdraw said latch where its resistance to movement is removed.

6. In a firearm of the type comprising a firing chamber, breech mechanism closing said firing chamber, and an action bar for operating said breech mechanism; a lock for said action bar, a hammer, a main spring and a bifurcated main spring rod associated with said

hammer, a latch for said action bar normally withdrawn from effective position on the forward movement of said hammer by engagement with one arm of said bifurcated main spring rod, but adapted to deflect and tension said arm when held by said action bar, and to be subsequently withdrawn by the return of said arm to normal position.

CRAWFORD C. LOOMIS.
